(57) CLAIM

The ornamental design for a portion of a golf club head, as shown and described.

DESCRIPTION

FIG. 1 is a toe side perspective view of a portion of a golf club head showing my new design;

FIG. 2 is a heel side perspective view thereof;

FIG. 3 is an elevational view thereof;

FIG. 4 is a toe side perspective view of a portion of a golf club head showing a second embodiment of my new design;

FIG. 5 is a heel side perspective view thereof; and,

FIG. 6 is an elevational view thereof.

The broken line immediately adjacent to the shaded area represents an unclaimed boundary of the design. The broken line showing of the remainder of the golf club head is for illustrative purposes only and forms no part of the claimed design.
